CLAIM

The ornamental design for a mirror, as shown and described.

DESCRIPTION

FIG. 1 is a front elevational view of a mirror, showing my new design;

FIG. 2 is a bottom view of the mirror of FIG. 1, the top and sides being identical; and,

FIG. 3 is an enlarged sectional view of the mirror of FIG. 1 taken along line 3—3 in the direction of the appended arrows.

1 Claim, 2 Drawing Sheets

FIG. 1
